ORNAMENTAL RAILING

Louis Blum, 2312 Tilbury St., and William J. Horgan, Jr.,
1299 Folkstone Drive, both of Pittsburgh, Pa.

Filed Dec. 13, 1963, Ser. No. 77,787

Term of patent 14 years

(Cl. D13—7)

FIG. 1 is a perspective view of a railing embodying our new design; and

FIG. 2 is a cross-sectional view taken on line II—II of FIG. 1, with a portion broken away for convenience of illustration.

The portions of the drawing showing the stairway in dotted lines are for illustrative purposes only.

We claim:

The ornamental design for an ornamental railing, as shown and described.
